UNITED STATES PATENT OFFICE.

MARTHA M. MAIDER, OF AKRON, OHIO.

SHOULDER-STRAP FASTENER.

Application filed November 17, 1926. Serial No. 148,851.

This invention relates to certain new and useful improvements in shoulder strap fasteners, and has more particular reference to an improved device for fastening the shoulder straps of undergarments in proper position upon the shoulders of the wearer.

The primary object of the present invention is to provide a fastener of the above kind which is extremely simple and durable 10 in construction as well as efficient in operation.

A more specific object is to provide a shoulder strap holder embodying an improved fastener of the combined clasp and pin type, the clasp element being engageable with the shoulder strap of the undergarment, and the pin element being engageable with an outer garment so that the shoulder strap is effectively held against lateral shifting on 20 the shoulder of the wearer.

Still another object is to provide a fastener of the above kind wherein the clasp element engages the shoulder strap to resist longitudinal movements of the latter through 25 the clasp and at the same time allow the longitudinal edge portions of the shoulder strap to be free, thus giving freedom of movement to the wearer's shoulder without causing material discomfort.

Another object is to so construct the clasp element as to permit neat curling of the longitudinal edge portions of an excessively wide shoulder strap in the ends of the clasp element so that the present fastener may 30 accommodate shoulder straps of varying widths, in a practical manner.

Other objects will become apparent as the nature of the invention is better understood, and the same consists in the novel 40 form, combination and arrangement of parts hereinafter more fully described, shown in the accompanying drawing and claimed.

In the drawing, wherein like reference numerals indicate corresponding parts throughout the several views,

Figure 1 is a view illustrating a fastener constructed in accordance with the present invention operatively engaged with each of the shoulder straps of an undergarment, the pin elements of the fasteners being open 50 ready for engagement with the shoulder portions of an outer garment to be donned by the wearer;

Figure 2 is an enlarged fragmentary view 55 showing one of the fasteners in elevation and operatively engaged with an outer garment

and a shoulder strap, such shoulder strap and outer garment being in transverse section;

Figure 3 is a view somewhat similar to 60 Figure 2 with the pin element open prior to engagement with the outer garment, and the clasp element in its extended or released condition wherein the insertion of the shoulder strap is freely permitted;

Figure 4 is a view somewhat similar to 65 Figure 3 with the clasp element partly returned to normal clasping condition after insertion of the shoulder strap, and showing 70 how the longitudinal edge portions of an excessively wide shoulder strap are curled in the ends of the clasp element when the fastener is employed in connection with such an excessively wide shoulder strap; and

Figure 5 is a greatly enlarged elevational 75 view of the fastener alone.

Referring more in detail to the drawing, the present fastener embodies a strip or piece of resilient metal, preferably resilient wire, bent in a novel manner to provide a clasp for 80 reception of or engagement with the shoulder strap or straps, and the major portion of a pin fastener for engagement with the adjacent shoulder portion of an outer garment, the remaining portion of the pin fastener 85 consisting of a pin keeper or guard rigidly fastened to an end of the piece of metal or resilient wire. As shown, the clasp portion or element of the fastener consists of a straight bar 5 constituting an intermediate 90 portion of the piece of wire and over which the shoulder strap S is adapted to be placed as shown in Figures 2 to 4 inclusive, and inwardly extending clasping arms 6 integral with and overlying the respective end portions 95 of the bar 5. The inner ends of the arms 6 terminate in spaced relation adjacent the center of the bar 5 so that the shoulder strap may be readily passed therebetween for engagement with the bar 5 and positioned between said 100 bar and the arms 6 as shown. The piece of wire is so bent that the resilient integral connections between the outer ends of the arms 6 and the respective ends of the bar 5 are in the form of relatively large circular 105 open loops 7, whereby the arms 6 are spaced at the outer ends thereof from the bar 5 for a distance considerably greater than the thickness of the shoulder strap so that the latter is entirely free at its longitudinal edge portions when engaged with the fastener.

However, these arms 6 normally assume an

inwardly and downwardly extending position as shown in Figure 5 so that their inner ends are in close proximity to the adjacent portions of the bar 5 and will therefore have 5 clasp engagement with the shoulder strap adjacent to and at opposite sides of its longitudinal center. Thus, the shoulder strap will be effectively held against undue shifting and at the same time will be free at its 10 longitudinal edge portions so that the shoulder strap may give within reasonable limits for affording free movement of the wearer's shoulder without causing discomfort. It will be understood that by springing the 15 arms 6 away from the bar 5 as illustrated in Figure 3 the engagement of the fastener with the shoulder strap may be more readily effected, whereupon the arms 6 may be allowed to return to normal position in engagement with the shoulder strap. The arms are 20 shown in the act of returning to normal position, in Figure 4.

A very important function of the relatively large loop connections 7 is that the 25 same enables the use of the present fastener in connection with shoulder straps which are wider than the length of the bar 5. In such cases, the longitudinal edge portions of the shoulder strap may be conveniently and 30 neatly curled up in the loops 7 as indicated in Figure 4. Naturally, if undergarments are worn which provide more than one shoulder strap upon each shoulder of the wearer, the several shoulder straps may be 35 engaged in the clasp so that relative displacement of the shoulder straps engaged thereby is effectively prevented and they will therefore be maintained in neat superimposed relation so as to present a neat appearance.

The pin element consists of similar arms 40 8 integral with and extending in upwardly diverging relation from the inner ends of the clasp arms 6, a horizontal pin 9 parallel with the clasp bar 5 and integrally connected at one end with the upper end of one of the arms 8 by a coiled integral connection 10 forming a spring which normally tensions the pin element 9 to move upwardly to an 45 open position as in Figures 3 and 4, and a suitable keeper or guard 11 rigidly attached to the upper end of the other arm 8 and behind which the free pointed end of the pin 9 is engageable for retaining the latter in 50 downwardly sprung closed position as in Figures 2 and 5, whereby the pin 9 is maintained in its position penetrating the shoulder portion 12 of an outer garment.

In use, the fastener is engaged with the 55 shoulder strap such engagement being facilitated by springing the arms 6 upwardly as indicated in Figure 3. With the fasteners engaged with the shoulder straps in this manner, the pins 9 thereof will be left open as indicated in Figure 1, whereupon

the outer garment is donned. The pins 9 are then passed through the shoulder portions of the outer garment and then engaged behind their respective guards or keepers 11, and the shoulder straps and fasteners are 70 then effectively held against lateral displacement so that the shoulder straps are maintained properly positioned upon the shoulders of the user.

From the foregoing description it is believed that the construction and operation as well as the advantages of the present invention will be readily understood and appreciated by those skilled in the art.

Minor changes may be made without departing from the spirit and scope of the invention as claimed.

What I claim as new is:—

1. A shoulder strap fastener comprising a clasp embodying a strap bar and clasp arms overlying the strap bar and resiliently connected at their outer ends to the ends of said strap bar, the inner ends of said clasp arms normally engaging the intermediate portion of the strap bar and terminating in 90 spaced relation, and a pin fastener carried by said arms.

2. A shoulder strap fastener comprising a clasp embodying a strap bar and clasp arms overlying the strap bar and resiliently connected at their outer ends to the ends of said strap bar, the inner ends of said clasp arms normally engaging the intermediate portion of the strap bar and terminating in 95 spaced relation, and a pin fastener carried by said arms, the resilient connections between the ends of the bar and the arms embodying relatively large open loops adapted to have the longitudinal edge portions of a shoulder strap curled up therein when the shoulder strap is wider than the length of the strap bar.

3. A shoulder strap fastener comprising a clasp embodying a strap bar and clasp arms overlying the strap bar and resiliently connected at the outer ends to the ends of said strap bar, the inner ends of said clasp arms terminating in spaced relation, and a pin fastener carried by said arms, said arms being tensioned to normally extend inwardly and downwardly for binding the shoulder strap in engagement with the strap bar at points adjacent the longitudinal center of said shoulder strap and for leaving the longitudinal edge portions of said strap free.

4. A shoulder strap fastener embodying a single piece of resilient wire bent to form a clasp and the major part of a pin fastener, said clasp comprising a strap bar and in-turned clasp arms carried by the ends of the strap bar and overlying the respective end portions of the latter, said pin fastener comprising upwardly diverging supporting arms extending upwardly from the inner ends of the clasp arms and one having an inwardly

projecting extension on its upper end in the form of a pin, and a keeper for said pin on the upper end of the other supporting arm.

5. A shoulder strap fastener embodying a single piece of resilient wire bent to form a clasp and the major part of a pin fastener, said clasp comprising a strap bar and in-turned clasp arms carried by the ends of the strap bar and overlying the respective end portions of the latter, said pin fastener comprising upwardly diverging supporting arms

extending upwardly from the inner ends of the clasp arms and one having an inwardly projecting extension on its upper end in the form of a pin, and a keeper for said pin on ¹⁵ the upper end of the other supporting arm, said clasp arms being inclined inwardly to grip a shoulder strap only at their inner ends.

In testimony whereof I affix my signature.

MARTHA M. MAIDER.
